UNITED STATES PATENT OFFICE.

ADDISON E. AUGUSTINE, OF HACKENSACK, NEW JERSEY, ASSIGNOR TO CHESTER MACHINE CO. INC., OF NEW YORK, N. Y., A CORPORATION OF NEW YORK.

DRYING BLOWER FOR ENVELOPE-MAKING MACHINES.

1,423,297.

Specification of Letters Patent. Patented July 18, 1922.

Application filed February 24, 1920. Serial No. 360,967.

To all whom it may concern:

Be it known that I, ADDISON E. AUGUSTINE, residing at Hackensack, in the county of Bergen and State of New Jersey, have 5 invented certain new and useful Improvements in Drying Blowers for Envelope-Making Machines, of which the following is a specification.

This invention relates to a drying blower 10 for envelope-making machines.

An object of the invention is to provide a simple and efficient means for drying the freshly gummed portions of the envelopes.

A further object is to provide a drier device 15 employing a fan and being of a character such that the air blast from the fan will be directed against the envelopes in an efficient manner.

A further object is to provide a drying 20 blower which may be constructed as a part of the envelope-making machine and which may, if desired, be driven by a moving part of the machine.

A further object is to construct the drying 25 blower so that it includes an air box which is formed separately from the fan element and which is capable of being readily removed from the fan element and from the remainder of the machine whenever de- 30 sired.

Other objects and aims of the invention, more or less specific than those referred to above, will be in part obvious and in part 35 pointed out in the course of the following description of the elements, combinations, arrangements of parts and applications of principles, constituting the invention, and the scope of protection contemplated will be indicated in the appended claims.

40 In the accompanying drawings which are to be taken as a part of this specification, and in which I have shown merely a preferred form of embodiment of the invention:—

45 Figure 1 is a diagrammatic view illustrating in side elevation a portion of an envelope-making machine, a drying blower constructed in accordance with this invention, being illustrated in operative association therewith.

Figure 2 is a side elevational view, partly in section, of the air box appearing in Fig. 1, and

50 Figure 3 is a top plan view of the structure seen in Fig. 2.

In envelope-making machines usually an endless chain is provided having fins thereon forming a plurality of stalls L into which is fed the newly gummed envelopes 1. The chain moves about spaced rollers 2 and 3 60 on a suitable frame member 4, the envelopes being fed into the stalls L at the upper end of the chain, as at the point 5, and traveling with the chain in the direction of the arrows. The envelopes finally leave the 65 chain at the point 6 and fall into suitable receiving means. The travel of the chain is slow so that the period of time during which the envelopes remain in the stalls L is intended to be sufficient to allow the new gum 70 to dry. In order to hasten the drying, and thereby also to facilitate the use of shorter chains, or faster moving chains, than heretofore, it has been found desirable to provide artificial drying means. A simple and 75 effective form of drying means is herein illustrated and forms the basis of this invention. It consists in a rotary air fan G to which is connected an air box H. The fan may be of any type but is preferably of 80 the type substantially as indicated, having a discharge nozzle portion 7 through which the air is delivered into the box H. The box H is provided with a collar portion 8 adapted to detachably but tightly engage 85 over the nozzle portion 7 of the fan so that all of the air from the fan is delivered into the interior of the box. The construction and arrangement of the parts of the box is clearly seen in Figs. 2 and 3 of the draw- 90 ings, wherein it will be noted that the upper wall, as 9, is inclined substantially to conform to the path of movement of the envelopes. This wall is formed with a multitude of perforations, as 10, therethrough 95 through which the air from the fan is directed upwardly against the passing envelopes.

The box is preferably largest at its end nearest the fan and tapers gradually to a 100 smaller size at its end furthest from the fan. The purpose of this arrangement is to produce a more uniform discharge of air from all of the apertures 10. The direct blast of air from the fan will naturally be 105 in a direction toward the reduced end of the box. The reduction in size and the consequent less number of apertures 10 at the far end of the box will cause the air to bank, or pile up, until the pressure is substantially 110

uniform throughout the interior of the box. The air blast from each of the apertures 10 will be substantially uniform, and the position of the wall 9 insures that the blasts from 5 all of said apertures 10 will be directed upon the passing envelopes.

A maximum degree of efficiency is thus attained so that it will be possible to use a comparatively small fan to provide all of 10 the air required.

The fan may be driven in any suitable manner, either by a moving part of the envelope-machine mechanism, or by an independent motor. As an example, it is herein 15 illustrated to be driven by a wheel 11 forming a part of the envelope-machine mechanism, a belt 12 extending from the wheel 11 to the fan pulley 13.

The blower device may be supported in 20 any appropriate manner but is preferably supported by the frame of the envelope-machine so that it can be moved as an entity therewith. For this purpose the drawing shows the fan to be provided with suitable 25 ears 14 which are attached by bolts, or screws, to the frame work of the machine.

The engagement of the collar 8 over the nozzle 7 will hold the air box H in position upon the fan and will permit convenient 30 removal of the air box whenever occasion may require.

As many changes could be made in this construction without departing from the scope of the invention as defined in the following 35 claims, it is intended that all matter contained in the above description or shown in the accompanying drawings, shall be interpreted as illustrative only and not in a limiting sense.

Having thus described my invention, what I claim as new and desire to secure by Letters Patent is:—

1. In an envelope-making machine having a carrier for the newly gummed envelopes, the combination therewith of a drying blower having parts by which to direct a blast of air against the envelopes carried by said carrier, drive connections between the machine and said drying blower, and 50 means by which said drying blower is connected with said machine to be carried thereby.

2. In an envelope-making machine having a carrier for the newly gummed envelopes, the combination therewith of a drying blower comprising a fan, an air box into 55 which air is delivered by the fan, said air box having openings therein through which

the air is directed from the box against the envelopes carried by said carrier, and said air box being of a relatively large size adjacent its point of connection with said fan and of relatively reduced size further from said point of connection with the fan for the purpose set forth.

3. In an envelope-making machine having a carrier for the newly gummed envelopes, the combination therewith of a drying blower comprising a fan, an air box into which air is delivered by the fan, said air box 70 having openings therein through which the air is directed from the box against the envelopes carried by said carrier, and said air box being separately formed and detachable from said fan.

4. In an envelope-making machine having a carrier for the newly gummed envelopes, the combination therewith of a drying blower comprising a fan, an air box into which air is delivered by the fan, said air box 80 having a plurality of openings therein through which the air is directed from the box against the envelopes carried by said carrier, said openings providing a greater area of discharge for the air from said box 85 nearest to said fan and relatively less area of discharge further from said fan.

5. An air box for drying blowers comprising a box otherwise closed on all sides but having an air receiving opening in one 90 wall and having a plurality of air discharge openings in another wall, the air discharge openings providing a greater area of discharge for the air nearest to said air receiving opening and relatively less area of 95 discharge further from said air receiving opening.

6. An air box for drying blowers comprising a box otherwise closed on all sides but having an air receiving opening in one wall 100 and having a plurality of air discharge openings in another wall, the air discharge openings providing a greater area of discharge for the air nearest to said air receiving opening and relatively less area of discharge further from said air receiving opening, and said box being of a size greatest nearer said air receiving opening and being tapered to a smaller size further from said air receiving opening.

In testimony whereof I affix my signature in the presence of two witnesses.

ADDISON E. AUGUSTINE.
